United States Patent Office

Des. 220,017
Patented Feb. 23, 1971

220,017

ASHTRAY

Loran L. Laughlin, 2541 Maywood Drive,
Salt Lake City, Utah 84109

Filed Aug. 28, 1969, Ser. No. 18,904

Term of patent 14 years

Int. Cl. D27—03

U.S. Cl. D85—2

FIG. 1.

FIG. 2.

FIG. 3.

FIG. 4.

FIG. 1 is a perspective view of the ashtray showing my new design;

FIG. 2 is a side elevation thereof with the other side being a mirror image;

FIG. 3 is a top plan view thereof; and,

FIG. 4 is a bottom view thereof.

I claim:

The ornamental design for an ashtray, as shown and described.
